METHOD AND APPARATUS FOR MAKING
LINED CONTAINERS

David Schmidt, Lakewood, Ohio, assignor to The
Dobeckmum Company, Cleveland, Ohio, a cor-
poration of Ohio

Application November 6, 1942, Serial No. 464,756

4 Claims. (Cl. 93—36.01)

1

This invention relates to improved method and apparatus for making such containers. More particularly, this invention relates to a container comprising a tubular carrier carton and a pre-formed tubular liner of non-fibrous film or the like and to the methods and apparatus for making such a container.

Heretofore, carrier cartons of fibrous stock, such as paperboard, chipboard, strawboard, kraft, and like paper stock, have commonly been lined with relatively structurally weak liners to enable containers of paper stock to be employed for packaging substances which could not be packaged in the unlined containers because of the permeable and absorptive nature of the paper stock. A basic requirement of such liners is, of course, that the liner be substantially inert and impervious to the contents to be packaged. Another requirement is that the liner be comparatively impermeable to extraneous elements, such as moisture vapor, for example, from which the packaged contents must be protected. Non-fibrous films, of which the regenerated cellulose film "cellophane" is the best-known example, will usually answer the foregoing requirements. Many types of non-fibrous films, varying widely in their chemical compositions and physical characteristics, are available to the art. By selecting a suitable non-fibrous film, either uncoated or coated to increase its impermeability, one may obtain a lining material which will exhibit sufficient inertness and imperviousness to water and most commonly packaged aqueous liquids, moisture vapor, and most oils, fats, greases, and the like.

An inexpensive manner of lining a carrier carton with non-fibrous film is to simply place a sheet of film within the open carrier carton so that the sheet will cover the inner surface of the bottom and walls of the carrier carton. There are several objections to such sheet-lined cartons. In the first place, the minimum amount of film lining the carton will be at the bottom and, thus, as the film tends to shrink and embrittle with age, an inherent characteristic of almost all non-fibrous films, the first place the film will tend to pull away from the support afforded by the carrier carton will be at the bottom, the point of maximum load of the contents. In the second place, the excessive folds and pleats of the sheet at the open mouth of the container render the liner extremely difficult, if not impossible, to seal satisfactorily and securely. It has been proposed to overcome the difficulties of film shrinkage and of sealing the lined cartons by placing

an oversized bag of film within the carrier carton. By making the bag oversize, the film will be substantially equally supported at all points during aging and the open mouth of the bag may be sealed manually or with bag sealing machinery. Such "bag in a box" containers have not been entirely satisfactory, however. The mouth of the bag must be unsupported in order to allow the mouth to be drawn together for closing and sealing in the usual manner. The mouth of the bag, therefore, must be held open during filling. Since many automatic filling machines are not equipped with mechanical fingers to hold the bag mouth open, the "bag in a box" containers must often be filled manually, a slow and laborious process. Otherwise, the contents to be packaged are likely to sift or spill between the liner and the carton. Also, the raw and absorptive edges of the carrier carton are exposed during filling. Thus, if fluids which would discolor the paper carrier cartons are to be packaged, extreme care must be used to avoid spilling the fluid during filling. Otherwise, even though the liner is securely sealed, the carrier carton will appear to be a "leaker" and the package will be unsalable. Further, to seal the bag securely, the mouth of the bag must be distended so that opposite walls are brought together. This requires either expensive automatic machinery or tedious manual operations.

It is the object of my invention to provide a lined carton which will afford the advantage of a bag lined container of the prior art, namely, that the oversized bag is supported at all points by the carrier carton, and which will eliminate the above enumerated disadvantages of filling and sealing such containers. It is another object of my invention to provide a loose, preformed tubular liner for a carrier carton which may be securely sealed by a cap type of closure, thus eliminating manipulation of the liner after filling. It is a still further object of my invention to provide a lined container which is particularly adapted to employ a non-fibrous film liner and which may be opened without destroying a liner which protects the carrier carton.

I accomplish the foregoing objects of my invention by employing a preformed liner element, preferably a bag of non-fibrous film, which is inserted in the carrier carton so that an open end of the liner extends beyond an open end of the carrier carton. I then turn the protruding open end of the liner inside out so that the open tubular end is turned over the edge of the carton and extends down its outer wall.

Especially where, as in the preferred form of

2

55

my invention, the inside-out portion of the tube fits smoothly and snugly against the outside wall of the carton, the operation of positively turning a tube of sheet material inside out without seriously creasing or tearing the tube seemed a particularly difficult problem. It is, therefore, a further object of my invention to provide a method of turning a tube of sheet material inside out over the open end of a carrier carton, with positive mechanical means and without tearing or straining the tube. I accomplish this object of my invention by mechanically expanding beyond the inside periphery of the carton substantially all portions of the periphery of the tube just above the edge of the carton. Then, by simultaneously drawing all parts of the expanded portion of the liner along the outside wall of the carton, the protruding portion of the tube will be turned inside out over the open end of the carton.

It is a still further object of my invention to provide a simple mechanism which will turn a liner tube inside out over the open end of a tubular carton according to my method.

From the foregoing, it should be apparent that a lined carton made according to my invention possesses several advantages. First, by employing a liner having an open tubular end turned inside out over the open end of a carrier carton, a liner will be fitted to the carton without necessarily being fastened to the carton by adhesive. Thus, a liner of nonfibrous film may shrink without being subjected to possible localized stresses caused by adhesive and, at the same time, the liner will be supported by the walls of the carrier carton. Second, there is no protruding and unsupported end of the liner tube which must be held open manually or by mechanical fingers during filling. Thus, my lined container is adapted to be used on substantially all automatic filling machinery. Third, the raw edges of the carrier carton are protected by the turned-over open end of the liner. Thus, the carrier carton is less likely to be spoiled by spilling the contents during packaging. Fourth, by providing a liner having an open tubular end which, when turned inside out, will snugly engage the outside wall of the container, a smooth unwrinkled edge may be provided on the open end of the container. Thus, the container may be securely sealed with a cap type closure.

Other and further objects and advantages of my invention are as follows:

By employing a liner derived from a preformed tube of sheet material, the liner may be made, inexpensively and separately from the carrier carton, on standard tube and bag forming machinery. The longitudinal seam of this liner may be closely inspected.

My tubular liners and carrier cartons are assembled quickly and simply with relatively simple and inexpensive devices. Several advantages result from this fact. It is not necessary to assemble the containers until just prior to filling. Thus, the liners of non-fibrous films may be stored in humid or similar atmospheres which retard aging and embrittlement, while the carrier cartons may be stored in an atmosphere of a different humidity to avoid excessive shrinkage or swelling of the paper stock. Also, carrier containers, such as spirally wound paper tubes, are usually made locally to avoid shipping costs, while preformed tubes and bags are usually made at centralized points. Thus, the

elements of my container may be made on existing standard machinery and shipping of empty assembled containers may be avoided as much as possible.

The turned-over edge of my liner may extend down the outside wall of the carrier carton and may even be sealed across the bottom of the carton. By employing a reverse printed transparent film, an attractive, glossy, and dust-free outside surface will be provided which, in cases where opaque inks are employed, will permit very cheap uncoated and unglazed paperboard stock to be employed for the carrier carton.

The open ends of my containers may be closed with a sheet of transparent film. Thus, my container may be employed as a display container. Also, the closure of my container may be removed without destroying the liner element which protects the carrier carton.

Other and further objects of my invention should be apparent from the following specification, claims, and drawings, in which:

Fig. 1 is an elevation, partly in section, of one embodiment of a container made according to my invention.

Fig. 2 is an elevation, partly in section, of another embodiment of a container made according to my invention.

Fig. 3 is an elevation, partly in section, of one embodiment of a liner-turning mandrel made according to my invention.

Fig. 4 is an enlarged detail section taken from Fig. 3 showing an early stage of the operation of the liner-turning mandrel.

Fig. 5 is an enlarged detail section, similar to Fig. 4 but showing a later stage of operation of the liner-turning mandrel.

Fig. 6 is an enlarged detail section, similar to Fig. 4 but showing a still later stage of operation of the liner-turning mandrel.

Fig. 7 is a diametric cross-section of the operating portion of another embodiment of a liner-turning mandrel made according to my invention.

Fig. 8 is an enlarged detail section taken from Fig. 7 showing an early stage of operation of the liner-turning mandrel.

Fig. 9 is an enlarged detail section, similar to Fig. 8, showing a later stage of operation of the liner-turning mandrel.

Fig. 10 is a diametric cross-section of still another embodiment of a liner-turning mandrel made according to my invention.

Fig. 11 is an enlarged detail section taken from Fig. 10 showing a stage of operation of the liner-turning mandrel.

In the drawings, Fig. 1 shows a lined container in which the turned-over edge portion of the liner extends only partly down the outer wall of the carrier carton. In Fig. 1, 10 represents, in this instance, a carrier carton comprised of a spirally wound cylindrical wall portion 11 having one end provided with a spun-in flange portion 12 which serves as a seat for a bottom disk 13. The preformed tubular liner 15 is preferably a bag of non-fibrous film, which may be formed, for example, in the usual manner by tubing a sheet or web of the non-fibrous film along a longitudinal seam (not shown), cutting a bag length from the tubed web, and then folding and adhering an end portion of the bag length to the wall of the tube to form the transverse bottom seam 16. In order to allow material for shrinkage of the liner and to assure that the liner will be supported at all points by the carrier carton, the cir-

circumference of the liner 15 should be greater than the inner circumference of the carrier carton wall 11, and usually equal to or slightly larger than the outer circumference of the carrier carton wall. Thus, the liner 15 is circumferentially oversized for the carrier carton 10. The liner 15 should be inserted far enough into the carton 10 so that excess liner material will be provided across the bottom 13 and the liner wall will allow for shrinkage in vertical and diagonal directions as well as in circumferential directions.

In order to support the liner within the carrier, cover the raw edges of the open end of the carrier carton, and to provide the other advantages enumerated in the foregoing statement of the objects of this invention, the marginal portion 17 of the preformed tubular liner adjacent the open end thereof is turned inside out over the rim or edge 14 of the open end of the carrier carton so that the marginal portion 17 will cover the margin of the outer wall of the carrier carton adjacent the rim 14. Because the circumference of the liner 15 is preferably only slightly larger than the outer circumference of the wall 11, the liner margin 17 will fit rather snugly and the portion 18 of the liner which covers the rim 14 will be smooth and free of wrinkles. Because non-fibrous film is usually stored in a humid atmosphere to preserve flexibility and elasticity of the film, films will generally take a rather rapid initial set or shrinkage in the comparatively dryness of normal atmospheres. Thus, if the rim portion 18 of the liner is slightly wrinkled when the margin 17 is first turned inside out, the initial set of the film will smooth out such wrinkles in a few hours. The liner margin 17 is preferably unattached to the outer surface of the wall 11. Thus, no points of localized stress will be created in the margin 17 as the film takes its initial set and shrinks with further aging. Because the open end of the carrier carton 10 will "give" slightly, the snug margin 17 of the liner will not be likely to rupture with normal aging. If the margin 17 does split after excessive aging, no harm will be done to the functional portion of the liner inside the carton.

The lined carrier carton 10 is preferably closed by a cap type of closure 20, such as the ring of spirally wound paper tubing 21 having a spun-in flange 22 upon which a closure disk 23 is seated. The closure 20 is preferably lined with a sheet of non-fibrous film 25, similar to the film of the liner 15. Thus, the smooth sheet of liner stock 25 will seat on the smooth rim portion 18 of the liner 15 so that the container may be securely sealed by applying a suitable adhesive or solvent to lute or weld the joint between the closure liner 25 and the rim portion 18. If the lining stock is of heat-sealable material, the joint between the closure liner and the carton liner may be heat-sealed, preferably by applying and heat-sealing the closure liner prior to putting on the cap 20. The closure may be reinforced by employing a suitable adhesive between the carton liner margin 17 and a margin 27 (usually pleated) of the closure liner as well as by the frictional fit of the ring 21 against the outside wall of the lined carton 10.

The closure liner 25 is preferably unattached to the cap 20 in order to prevent localized stress during shrinkage of the film 25 and to permit the sealed container to be opened without destroying the liner 15. Thus, to open my sealed lined container, the cap 20 is slipped off, leaving the liner 25 stretched as a diaphragm over the open end

of the lined carrier carton. By simply cutting through the diaphragm of film 25, the container may be opened without destroying or rupturing the liner 15. The container may be reclosed by replacing the cap 20.

The lined carton 110 shown in Fig. 2 is similar to the carton 10 shown in Fig. 1, being comprised of a tubular wall portion 111 having a suitable bottom flange 112 and disk 113. The carton 110 is lined with a loose tubular bag liner 115 having a bottom seam 116 similar in proportion to the liner 15. The liner 115, however, is provided with a long margin 117 which is turned inside out over the rim 114 of the carton to provide a sealing seat 118 and then extends down the outside of the carton wall 111, the edges of the margin 117 being drawn together across the bottom of the carrier carton and joined together by the seam 119. Thus, the carrier carton 110 in this modification is completely covered, inside and out, by the tubular liner 115. By reverse printing on the smoothly fitting margin 117, a glossy, dust-resistant, and attractive outer wall and label may be provided. If the under surface of the margin 117 is completely printed over with opaque inks, the walls of the carton 110 will be completely masked, thus allowing cheap uncoated paper stock to be employed while providing a brilliantly colored outside wall for the container.

In order to employ the lined carton 110 as a display container, a sheet of transparent liner stock, similar to the material of the liner 115, is stretched across the open end of the carton 110 and may be sealed to the seat 118 in a suitable manner. The closure sheet 125 is also preferably provided with a pleated flange 127 which may be secured to the carton covering margin 117 by an adhesive and/or the friction ring 121. From the foregoing, it should be apparent that the closure 120 is similar to the closure 20, except that the closure disk 23 is omitted. The friction ring 121 may also be omitted, but it is generally preferred in order to provide the protective bead 122 and to mask the pleated margin 127.

From the foregoing, it should be apparent that lined containers made according to my invention have no loose unsupported liner portions. Thus, my containers are adapted for use on most automatic filling machines and may be closed and sealed securely. Further, because the turned-over margins protect the edge of the carrier cartons, no more than ordinary care need be exercised in filling the containers.

In the drawings, Figures 3 to 6 illustrate my method of turning a margin of a preformed tubular liner inside out over the open end of a carrier carton and the construction and operation of one embodiment of apparatus which may be operated to form a lined cylindrical carton according to my method. Other devices operable according to my method are shown in Figs. 7 to 9 and in Figs. 10 and 11. As will be explained, still other modifications of my liner turning mechanism may be made. Therefore, in the following description of my bag turning methods and the devices I have disclosed, all stated proportions, dimensions, materials, and the like, are not to be considered as limitations but merely as being illustrative.

In the bag turning device shown in Figs. 3 to 6, a fixed cylindrical mandrel sleeve 230 is adapted to receive a mandrel 240 which is telescopic within the mandrel sleeve and is provided with a stop 231 to limit the telescoping of the mandrel 240. The upper end of the mandrel sleeve 230 is provided with a downwardly and inwardly di-

rected bevel 232 to provide an outer camming rim 233. The outer diameter of the sleeve 230 is such that the diameter of the rim 233 will be slightly larger than the outer diameter of the overturned margin of the liner on a container assembled according to my method.

The mandrel 240 is provided with an annular beveled camming shoulder 241 located on the mandrel 240 so that when the mandrel engages the stop 231, the shoulder 241 will be received in the portion of the mandrel sleeve relieved by the bevel 232. From the point of the shoulder 241, the mandrel 240 extends upwardly and is tapered to form a container receiving portion.

When the mandrel 240 is axially displaced in the sleeve 230, an annular groove is provided to receive an expander comprising a ring of a tight coiled spring 250. The spring 250 is under a slight tension when engaging the mandrel 240 beneath the shoulder 241. The spring 250 is engaged between the shoulder 241 and the rim 233 to maintain the mandrel in the displaced position as shown in Fig. 3. The coil radius of the spring ring 250 is slightly larger than the difference between the radius of the point of the shoulder 241 and the rim 233 so that, when the mandrel is telescoped in the sleeve, the ring will be expanded annularly and the rim 233 will engage the spring inside the mean radius of the ring. A small amount of vertical pressure on the ring will cause the rim 233 to act as a cam to further expand the ring annularly.

To assemble a lined container according to my method with the mandrel 240 and sleeve 230, a tubular liner, in this instance a bag 215 of non-fibrous film, is opened so that its mouth may be slipped over the tapered portion of the mandrel 240 and pulled over the ring 250 and upper portion of the sleeve 230. In this instance, the bag 215 has an inside diameter equal to the outside diameter of the sleeve 230; accordingly, the bag, if it is of a non-fibrous film such as "cellophane," should be "fresh," i. e., the bag should have been stored under proper conditions so that the film is flexible and slightly elastic to permit the bag to be stretched over the expander 250 and to undergo the subsequent turning operations. A carrier carton 210 is then placed on the mandrel over the bag 215. The dimensions of the carton 210 are such that when the bottom 213 is supported by the mandrel 240, carton rim 214 will engage the bag 215 against the mandrel just above the shoulder 241. Thus, the carton rim will be supported by the mandrel 240. The outside diameter of the carton wall 211 is slightly less than the outside diameter of the sleeve 230. From the foregoing, it should be apparent that the taper of the container receiving portion of the mandrel not only allows the liner bag to be slipped over the mandrel easily but also provides a space for excess liner material when the liner is oversize. It should also be apparent that the length of portion 217 of the liner bag which is outside the carton determines the depth of the margin of the liner which is turned inside out over the rim of the carton.

To turn the tubular liner inside out over the rim of the carton, the bottom 213 of the carton is pressed to telescope the mandrel 240 in the sleeve 230. As shown in Fig. 4, the beveled shoulder 241 first expands the ring 250 annularly over the sleeve rim 233. Thus, the portion of the liner 215 which is unsupported by the carton wall 211 and which is immediately adjacent the rim 214, is expanded at all portions of its periphery be-

yond the inside periphery of the carton. The liner, as shown in Fig. 4, accordingly forms a smooth sealing seat 218 over the carton rim 214.

As the mandrel 240 is fully telescoped, the vertical pressure of the carton rim 214 on the ring 250 expands the ring 250 annularly over the sleeve rim 233 in the manner described above. As shown by the direction arrow in Fig. 5, this further expansion of the ring 250 may also rotate the coil of the ring; accordingly, the liner margin 217, which then wraps a substantial portion of the ring 250, is started to be turned inside out. To complete the turning of the liner margin 217, the ring 250 is then rolled along the outer wall of the carton, by the fingers of the operator or with suitable rollers 255, as shown in Fig. 6, until the margin is completely turned. The ring 250 is then removed from the carton and replaced in the groove between the shoulder 241 and the sleeve rim 233. The lined carton is ready for filling and sealing if the turned-over margin extends only partly down the outside wall of the carrier carton. If the turned-over margin is to completely cover the outside wall and bottom of the carton, as in Fig. 2, the free end of the tubular liner is, of course, gathered together and secured in a suitable manner.

A modification of my bag turning device is illustrated in Figs. 7 to 9 of the drawings. The bag turning device there shown is comprised of a mandrel sleeve 330 in which a mandrel 340 is telescopably mounted. The sleeve 330 is journaled for axial sliding movement in a finger supporting cylinder 360. In the embodiments shown, the sleeve 330 is movable in the fixed cylinder 360, although obviously the fixed and movable relationship of these members may be reversed.

The upper portion of the finger supporting cylinder 360 is provided with an internal annular groove 361 to receive the foot beads 356 of the expander pushing fingers 355. The cylinder 360 is counterbored from the top to the groove 361 to provide space for the swing of the fingers 355. A finger collapsing spring ring 362 is retained on the top of the cylinder 360 by means of the retainer ring 363.

The upwardly extending fingers 355 are each comprised of a blade 357 pivotally mounted in the groove 361 by means of the integral arcuate foot beads 356. The blades 357 are likewise arcuate in a horizontal section. By employing a plurality of fingers 355 (six are employed in the present embodiment shown in section, two being shown in section and two others being shown in invisible lines), the vertical blades 357 will constitute a segmented cylindrical sleeve. The fingers 355 are normally collapsed against the mandrel sleeve 330 by means of the finger-collapsing spring ring 362.

In addition to being slidably journaled in the cylinder 360, the mandrel sleeve 330 is provided with an internal collar 331 which is slidably keyed on the central shaft 365. The collar 331 also acts as a stop to limit the telescoping of the mandrel 340 in the sleeve 330. When the mandrel sleeve 330 is in its normally extended position, the radially protruding annular finger expanding cam 333 for the upper end of the sleeve is spaced vertically above the fingers 355. The under surface of the annular cam 333 is beveled outwardly so that when the sleeve 330 is telescoped into the cylinder 360, the cam will expand the normally collapsed fingers 355 into a segmented cylindrical sleeve, the outside diameter of the annular cam 333 being equal to the inside diameter of

the segmented cylinder formed by the fingers 355. To maintain the mandrel sleeve in its normal extended position, any suitable means, such as the relatively stiff compression spring 334, may be employed. The upper surface of the cam 333 is provided with a downwardly and inwardly beveled surface 332 so that the cam 333 will also act as a keeper for the expander rings.

The mandrel 340 is telescopably mounted in the sleeve 330 and is also provided with an internal collar 342 which is mounted on the central shaft 365. To maintain the mandrel 340 in its normally extended position, any suitable means may be employed, such as, for example, the relatively soft compression spring 343 which is engaged between the collars 331 and 342 against the central shaft set collar 366. The mandrel 340 is provided with an annular shoulder 341 spaced above the mandrel sleeve cam 333. The upper surface of the shoulder 341 serves as a carton receiving ledge or foot; the under surface of the shoulder 341 is beveled outwardly to serve as an expander camming surface. The outside diameter of the mandrel shoulder 341 is not greater than the outside diameter of the finger cam 333. Above the shoulder 341 the mandrel is tapered inwardly to provide a container receiving portion.

When the mandrel 340 is in its normal extended position, the spaced shoulder 341 and cam 333 provide a wide annular groove in which a plurality of coil spring rings are received. In this instance, three spring rings are employed, the uppermost expander ring 350 and two auxiliary rings 351 and 352. Because the rings are under a slight tension, the rings will maintain their vertical disposition about the mandrel 340. When the mandrel 340 is telescoped in the mandrel sleeve 330, the upwardly beveled camming under surface of the shoulder 341 will press the vertically disposed lowermost of the rings against the inwardly beveled keeper surface 332 of the cam 333 and expand the rings outwardly; the uppermost of the rings, the expander ring 350, obviously, being expanded most. The collars 342 and 331 are set so that the telescoping of the mandrel 340 in the sleeve 330 will stop when the first auxiliary ring has been expanded to an outside diameter approximately equal to the outside diameter of the cam 333, as shown in Fig. 8.

To assemble a container on my device as illustrated in Figs. 7 to 9, a suitable tubular liner, for example, the bag 315, is slipped over the container receiving portion of the mandrel, the shoulder 341, and the cams 333, the length of the tubing 317 which depends from the shoulder 341 determining the depth of the margin of the liner to be turned inside out over the rim of the carrier carton. A tubular carrier carton 310, having an inside diameter about equal to the outside diameter of the mandrel immediately above the shoulder 341 and an outside diameter not appreciably greater than the outside diameter of the cam 333, is then placed over the bag 315 so that the rim 314 of the carton is received on the annular foot of the shoulder 341. By thus seating the carton on the foot provided by the shoulder, the unsupported periphery of the liner immediately adjacent the rim of the carton is started to be expanded beyond the inside periphery of the carrier carton. By then fully telescoping the mandrel 340 in the mandrel sleeve 330, the expander spring ring 350 is expanded beyond the outside diameter of the cam 333 in the manner described above; the ring 350 will pull the liner over the carton rim 314 to provide a sealing seat

318, as shown in Fig. 8. To turn the margin 317 inside out over the open end of the carton 310, continued downward movement of the mandrel 340 will telescope the sleeve 330 in the cylinder 360 so that the cam 333 will expand the fingers 355 into a segmented cylindrical sleeve inside the depending liner margin 317. As the sleeve 330 continues to telescope, the ends of the finger blades 357 will engage the expander ring 350, further expanding the ring 350 over the point of the shoulder 341 and forcing the ring 350 along the carton wall 311 to turn the margin inside out, as shown in Fig. 9. When the liner margin 317 is completely turned inside out, the mandrel 340 and sleeve 330 are returned to their extended position, the fingers again collapsing against the sleeve, the expander ring 350 is replaced in the groove between the shoulder 341 and cam 333, and the lined carton is removed from the mandrel.

Another embodiment of my liner turning device is illustrated in Figs. 10 and 11, in which a mandrel 440 is telescopably mounted in a fixed mandrel sleeve 430 suitably secured to a base. A base plate 431 serves as a limit for the telescoping movement of the mandrel 440. In addition to being journaled in the sleeve 430, the mandrel 440 is provided with an internal collar 442 which is slidably keyed on the central shaft 465 secured to the base plate 431. To maintain the mandrel 440 in its normal extended position, a compression spring 443 is engaged between the collar 442 and the base plate 431. The extension of the mandrel 440 is limited by the stop washer 466 bolted to the upper end of the shaft 465.

A finger supporting ring 460 is fixed on the sleeve 430 and is provided with an inner annular groove 461 to receive the arcuate foot beads 456 of the expanding fingers 455. The ring 460 is counterbored to the groove 461 to allow for the swing of the fingers. The upwardly extending fingers 455 are similar to the fingers 355 described above, except that the blades 457 are provided with lugs 463 to retain the spring ring 462, which collapses the fingers 455 against the mandrel 440 when the mandrel is in its normal extended position. Also, in this embodiment, the upper edges of the blades 457 should be free from burrs or roughness and are preferably rounded, as shown in Fig. 11.

The mandrel 440 is provided with an annular protruding shoulder 441 which, when the mandrel is in its normally extended position, is located above the collapsed fingers 455. The under surface of the shoulder 441 is beveled outwardly to serve as a camming surface to expand the fingers 455. The upper surface of the shoulder serves as a carton-receiving foot. Above the shoulder 441 the mandrel 440 is tapered slightly to serve as a container receiving portion.

To assemble a container on my device as shown in Figs. 10 and 11, a tubular liner, in this instance the bag 415, is slipped over the container receiving portion of the mandrel and the shoulder 441, the length 417 depending from the shoulder 441 determining the depth of the margin to be turned inside out. A carton 410 is then placed over the bag 415 so that the rim of the carton is seated on the foot portion of the shoulder 441 and is supported by the mandrel wall immediately above the shoulder 441. Thus, the shoulder 441 expands the periphery of the portion of the tubular liner, which is unsupported by the inner carton wall and adjacent the rim of the carton, beyond the inside periphery of the tubular wall 411. To turn the liner inside out over the rim of the carrier carton,

the mandrel 440 is telescoped in the sleeve 430. As the mandrel is telescoped, the fingers 455 are expanded into a segmental cylindrical sleeve inside the depending liner margin 417 by the camming under surface of the shoulder 441. As the mandrel continues to be telescoped, the blades 457 will draw the margin 417 along the outside wall of the carrier carton, turning the margin 417 inside out as it slips over the edges of the blades 457, as shown in Fig. 11. When the margin 417, or so much of it as desired, has been turned inside out, the telescoping force on the mandrel 440 is released, the spring 443 returns the mandrel to its normal extended position, the fingers 455 being withdrawn and collapsing, and the lined carton is removed.

From the foregoing, it is apparent that the success of my invention lies in positively expanding beyond the inside periphery of the carrier carton at least the portion of the tubular liner which is unsupported by the inside wall of the carrier carton immediately adjacent the open end of the carton and then simultaneously drawing all parts of the expanded portion of the liner along the outside wall of the carton. In Figs. 3 to 6 and 7 to 9, only the portion of the margin immediately adjacent the carton rim is so expanded. In Figs. 10 and 11, the whole margin is expanded. In all three disclosed embodiments of my assembling devices, the entire periphery is expanded simultaneously. It should be apparent that the periphery to be expanded could also be expanded progressively, as, for example, rotating an expanding finger around the mandrel adjacent the rim of the carton and providing means to maintain the liner in its expanded position. Thus, the term "expanding" and like terms employed in this specification and the claims is to be understood to include progressive as well as simultaneous expansion unless the term is otherwise limited. However, once the liner is expanded beyond the inside periphery of the carrier carton, all parts of the expanded portions should be turned inside out simultaneously.

From the explanation of the principle of my method and the disclosed embodiments of my turning devices, it should be apparent that my turning devices are not limited to the specific mechanisms disclosed. For example, it is not necessary that the container supporting mandrel be telescopic into a sleeve. Rather, the mandrel may be fixed and the expander may be expanded by means other than the wedging means shown. For example, by placing within the tubular liner a spring ring, having a mean ring diameter slightly greater than the outside wall of the carrier carton, and then pressing the spring ring against the rim of the carton, the liner will be expanded according to my method, the curved inner surface of the spring ring engaged against the rim of the carton acting as the ring expanding cam.

As should be apparent from Fig. 11, containers made according to my invention are not limited to those as shown in Figs. 1 and 2 in which the liner margin is entirely turned inside out. For example, by drawing the margin 417 along the outside wall of the carton until the end of the margin is even with the carton rim and then withdrawing the fingers 455, the carton will be provided with a two-ply overturned margin. Further, it is not necessary to close the lined carton with a cap or sheet which is the equivalent of a cap type of closure. The lined carton may be sealed by the liner tube. For example,

by employing a long liner tube and only turning a portion of the unsupported liner inside out over the outer wall of the carton, as at the stage shown in Fig. 11, a free skirt of the liner tube will remain; said skirt may then be drawn together and sealed over the open mouth of the lined carton.

It is to be understood that the terms "tube" and "tubular," as employed in this specification and in the claims, refers to an elongated, relatively thin-walled hollow body in which the longitudinal elements of the wall or walls are parallel. Thus, my containers are not necessarily of circular cross-section, but may have a rectangular or similar polygonal cross-section, and my carrier cartons are not limited to spirally wound tubular cartons, but may be tubular cartons of the collapsed or set-up type.

As pointed out above, my method of lining containers is particularly adapted for the use of liners of non-fibrous films, such as, for example, films of regenerated cellulose, cellulose ethers and esters, or mixed cellulose ethers and esters; chlorinated rubber or rubber hydrochloride films (such as the film known commercially as "Pliofilm"); polyvinyl films (such as the films known commercially as "Vinylite" and "Koroseal"); polyamide films (such as the film known commercially as nylon); and the like. While non-fibrous films are generally preferred, any flexible sheet, fibrous or non-fibrous, may be employed, however, if the sheeting possesses the requisite inertness and imperviousness. Glassine or like impregnated or coated paper, parchment paper, paper laminated to film or foil, and the like are examples of fibrous sheet materials which may serve as suitable lining stock. The characteristics of the sheeting as to elasticity and aging should be taken into account in determining the dimensions of the tube. For example, if a liner of inelastic glassine is employed, the tube should be sufficiently oversize with respect to the carrier carton to permit the tube to undergo the turning operation without splitting. If a "cellophane" film is employed, the film, when fresh, is usually sufficiently elastic to allow for the turning operation, but the tube should be sufficiently oversize to allow for shrinkage when the tube ages. If the tube is of cellulose acetate film, aging is seldom a problem, and the tube need only be oversize in order to insure that the film will not be ruptured by the load of the contents. If a "Pliofilm" tube is employed, the tube may be actually undersize with respect to the carton, since such film is usually sufficiently elastic to stretch until it is supported by the carton before it will be ruptured by the load of the contents.

It is usually unnecessary to secure my liner to the carrier carton wall, since the turned-over margin usually affords a sufficient frictional anchor for the liner. When the turned-over margin is short and the container is filled with heavy, adherent contents, such as hardened vegetable oils or lard, for example, it may be advantageous to adhere the margin to the carrier carton. A convenient location for the margin anchoring adhesive is on the rim of the carton.

While my tubular carrier cartons are usually of paper stock, it is to be understood that any suitable rigid or semi-rigid tubular receptacles of other materials, such as sheet metal, for example, may be employed as a carrier receptacle.

From the foregoing, it is apparent, therefore, that my invention is not limited to the embodiments disclosed, either in whole or in part, but

that my invention may be modified by those skilled in the art within the scope of the appended claims without departing from the spirit or scope of my invention.

What is claimed is:

1. The method of lining a container comprising the steps of inserting a lining tube of flexible sheet material in the open end of a tubular receptacle, allowing an unsupported margin of said tube to extend out of said receptacle, simultaneously positively and uniformly expanding all portions of the periphery of said margin immediately adjacent the rim of the open end of said receptacle beyond the inside periphery of said rim, and then simultaneously positively and uniformly drawing all parts of the expanded portion of said margin along the outside wall of said receptacle to turn said margin inside out, in which said unsupported margin is longer than the length of said container and in which the step of drawing said margin along the wall of said container is continued along the entire length of the wall and including the step of gathering the mouth of said liner tube together across the bottom of said receptacle to completely cover said receptacle with said liner.

2. In a device of the class described, a mandrel, a container receiving portion on said mandrel to support the inside wall of a container on said portion, an annular shoulder on said mandrel, an annular expander on said mandrel, and means to force said expander over said shoulder to expand said expander.

3. In a device of the class described, a mandrel,

an annular shoulder on said mandrel, an expander movable longitudinally along said mandrel comprising a spring ring, and means to force said ring over said shoulder to expand said ring.

5. 4. In a device of the class described, a mandrel, a shoulder on said mandrel, expansible fingers collapsed against said mandrel, and means to move said fingers over said shoulder to expand said fingers.
